ELECTROMECHANICAL RESONATING DEVICE

Application filed May 21, 1930, Serial No. 454,490, and in France April 18, 1930.

It is old to superimpose on electric supply lines, currents generally of high frequencies different from that of the supply system, with a view to remotely controlling receiving apparatus used for changing tariff meters or for actuating switches.

The receiving apparatus used for this type of telecontrol are generally tuned mechanically or electrically to the frequencies of the superimposed signalling currents.

To this effect, it has already been proposed to utilize polarized receivers fitted with vibrating reeds or tuning forks tuned to the frequencies of the superimposed currents and energized by circuits likewise tuned to such frequencies.

The present invention relates to a resonating electro-mechanical receiver which is particularly suited to controlling a plurality of co-ordinated operations.

An example of the application of the invention to the combined control of two lighting circuits has been illustrated in the accompanying drawings wherein:

Fig. 1 illustrates diagrammatically a circuit arrangement in which is mounted an electro-mechanical device for controlling a set of lamps.

Figs. 2 and 3 illustrate diagrammatically in plan and part sectional elevation respectively the mechanical features of said electro-mechanical device.

Fig. 4 illustrates the several positions which the controlling switches may assume.

1 and 2 designate the supply cables on which the signalling currents are superimposed; 3 and 4 are the energizing coils for the receiver which are connected in series with a capacity 5, the whole being shunted across the cables 1 and 2. 6 is a mercury switch connected to a mercury reversing switch 7 which directs the current through a lamp 8 or a lamp 9 alternatively. The switch 6 is mounted on a shaft 14 which carries a finger 15 movable between two fixed stops 10 and 11. The reversing switch 7 is secured to a shaft 16 which carries a finger 17 movable between two fixed stops 12 and 13; 18 is a magnet which serves to polarize the vibrating reeds L₁, L₂, L₃ respectively tuned to

the frequencies F₁, F₂, F₃. The series connected coils 3 and 4 are mounted respectively on laminated yokes 19 and 20 which contact with the polar ends of the magnet 18 and which are separated from each other by an air gap. Three resilient metallic blades I₁, I₂, I₃ mounted respectively on the free ends of the reeds L₁, L₂, L₃, act respectively like pawls on three ratchet wheels R₁, R₂, R₃. The wheel R₁ is secured to two side gears of two differentials, the wheels R₂ and R₃ are secured respectively to the other side gear of each of said two differentials of which 21 and 22 are the pinion gears respectively mounted on the shafts 23 and 24. The shaft 23 is mounted fast on a quill shaft 25 carrying a pinion 26 which rotates the aforementioned shaft 14 through the medium of the gear train 27 and 28. The shaft 24 is locked on the shaft 29 which carries a pinion 30 rotating the aforementioned shaft 16 through the gear wheel 31.

The apparatus operates as follows:

The mercury switches 6 and 7 being respectively in the position shown at A₃ in Fig. 4, a current of frequency F₁ is superimposed on the cables 1, 2 and flows through the circuit 3, 4, 5 with which it is in resonance. The frequency F₁ lies between the frequencies F₂, and F₃. The blade L₁ enters into resonance and its vibrations, transmitted by the pawl I₁, cause the ratchet wheel R₁ to rotate in the clockwise direction as viewed in the direction of the arrow f. The lay shaft 23 is rotated in the same direction until the finger 15 bears against the stop 10. At this instant, the shaft 23 is arrested and the pinion 21 causes the side gear secured to the wheel R₃ to rotate in the opposite direction to R₁. Simultaneously, the shaft 24 not being able to rotate in the same direction as R₁ because the finger 17 presses against the stop 13, the pinion 22 rotates the sun wheel secured to R₂ in the opposite direction to R₁ whereby the lamp 9 is lighted and the wheels rotate so long as the current of frequency F₁ flows.

To light the lamp 8 and to extinguish the lamp 9, it is only necessary to superimpose a current of frequency F₂. The reed L₂ starts vibrating and rotates the wheel R₂ in the

counter-clockwise direction. The shaft 24 is then rotated in the same direction and, through the medium of the pinions 30 and 31, rotates the reversing switch 7 until the finger 17 presses against the stop 12. At this instant, the shaft 24 is locked and the pinion 22 rotates the sun wheel secured to R_1 in the opposite direction to R_2 . The second side gear secured to R_2 rotates, through the medium of the pinion 21, the side gear secured to R_3 in the same direction as R_2 and the switch 6 remains in its previous position. The two switches now occupy the positions shown at A_2 , and thus the lamp 8 glows whereas the lamp 9 is dark.

Finally, in order to extinguish the lamp 8, it is only necessary to superimpose a frequency of current F_3 . The reed L_3 starts vibrating and rotates the ratchet wheel R_3 in the counter-clockwise direction through the medium of the pawl I_3 . The shaft 23 is rotated in the same direction until the finger 15 presses against the stop 11. At this instant, the shaft 23 is locked and the pinion 21 rotates the side gear secured to R_1 in the opposite direction to R_3 . The result is that the shaft 24 is rotated in the same direction as R_1 until the finger 17 presses against the stop 13. The shaft 24 is then locked and the pinion 22 rotates the side gear secured to R_2 in the opposite direction to R_1 . The switches now occupy the respective positions indicated at A_3 and the cycle of operations may then be repeated.

35 The apparatus described might likewise be used advantageously for the remote control of circuit-breakers provided for switching transformers into or out of service, in particular on rural systems; said transformers being adapted to the power used.

The apparatus according to the invention possesses great advantages. In particular, it enables the natural frequencies of the reeds to be brought as closely together as desired, 45 and consequently likewise the frequencies of the superimposed currents which manifestly and in the majority of cases simplifies the methods of superimposition relied on.

50 When a current of frequency F_1 is superimposed, the reed L_1 starts vibrating and imparts a certain velocity to the wheel R_1 . If the blades L_2 and L_3 are tuned to frequencies lying on either side of F_1 and in the neighborhood thereof, they may likewise vibrate, with 55 a smaller amplitude to be sure than L_1 , but nevertheless to a sufficient extent to impart a low velocity to their respective wheels R_2 and R_3 or at least to make them advance by jerks. Notwithstanding this effect, the operation performed will be that corresponding to the frequency F_1 because the reed L_1 will impart to the wheel R_1 a velocity substantially greater than the velocity imparted to the wheels R_2 and R_3 respectively by the reeds L_2 60 and L_3 .

I claim:

1. In an electro-mechanical device of the class described, the combination with three vibrating reeds of different natural frequencies, of two differentials each comprising two side gears in mesh with a pinion gear, said differentials being coupled together through two of said side gears while the other side gear of each differential remains independent, two switch controlling shafts, a stub shaft mounted fast on each of said switch controlling shafts, and on which one of said pinion gears is mounted to be rotatable relatively thereto, means for limiting the rotation of said switch controlling shafts in both directions, and means for transmitting the vibrations of said reeds to said independent side gears and coupled side gears respectively.

2. In an electro-mechanical device of the class described, the combination with three vibrating reeds of different natural frequencies, of two differentials each comprising two side gears in mesh with a pinion gear, said differentials being coupled together through two of said side gears while the other side gear of each differential remains independent, two switch controlling shafts, a stub shaft mounted on each of said switch controlling shafts and on which one of said pinion gears is mounted to be rotatable relatively thereto, means for limiting the rotation of said switch controlling shafts in both directions, three toothed wheels secured respectively to said coupled and independent side gears, and three blades mounted respectively on said vibrating reeds and engaging with said respective toothed wheels to rotate same.

3. In an electro-mechanical device of the class described, the combination with three vibrating reeds of different natural frequencies, of two differentials each comprising two slide gears in mesh with a pinion gear, said differentials being coupled together through two of said side gears while the other side gear of each differential remains independent, two switch controlling shafts, a stub shaft mounted fast on each of said switch controlling shafts and on which one of said pinion gears is mounted to be rotatable relatively thereto, a finger carried by each of said switch controlling shafts, two fixed stops associated with each of said fingers for arresting the movement of the corresponding switch controlling shaft, and means for transmitting the vibrations of said reeds to said independent side gears and coupled side gears respectively.

4. In an electro-mechanical device of the class described, the combination with three vibrating reeds of different natural frequencies, of two differentials each comprising two side gears in mesh with a pinion gear, said differentials being coupled together through

two of said side gears while the other side gear of each differential remains independent, two switch controlling shafts, a stub shaft mounted fast on each of said switch controlling shafts, and on which one of said pinion gears is mounted to be rotatable relatively thereto, a finger carried by each of said switch controlling shafts, two fixed stops associated with each of said fingers for arresting the movement of the corresponding switch controlling shaft, three toothed wheels secured respectively to said coupled and independent side gears, and three blades mounted respectively on said vibrating reeds 15 and engaging with said respective toothed wheels to rotate same.
